D. B. Marks,

Artificial Leg.

No 10,611.

Patented Mar. 7, 1854.

UNITED STATES PATENT OFFICE.

DAVID B. MARKS, OF NEW YORK, N. Y.

ARTIFICIAL LEG.

Specification of Letters Patent No. 10,611, dated March 7, 1854.

To all whom it may concern:

Be it known that I, DAVID B. MARKS, of the city, county, and State of New York, have invented a new and useful Improvement 5 in Artificial Legs; and I do hereby declare that the following is a full, clear, and exact description of the same, reference being made to the accompanying drawings, making a part of this specification, in 10 which—

Figure 1, shows the limb and foot, in section, in two of the positions of walking; one of the positions being shown in black, and the other in red color. Fig. 2, shows the same, 15 bent as when the wearer is in a sitting posture. Fig. 3, is a side view of the curved bar, by which the movement of the knee-joint is controlled, with a section of the head of the rod and roller which are connected 20 with the foot. Fig. 4, is a front view of the same.

Similar letters of reference indicate corresponding parts in each of the several figures.

25 This limb is intended to perform, in walking, all the movements of the natural limb. In taking a step, the foot is brought flat to the ground, with a perfect rigidity of the knee joint, which is maintained until 30 the ankle is bent by the throwing forward of the body as the opposite leg takes the succeeding step. This bending of the ankle leaves the knee free to make the slight bend which is necessary to raise the heel from 35 the ground; and when the knee is thus bent, the ankle becomes stiff, with the toe raised to prevent its dragging during the early portion of the movement of the leg in taking the next step; and it remains stiff until it is 40 necessary, for the straightening of the knee and the throwing down of the toe, to bring the foot flat to the ground, both of which latter movements are effected simultaneously.

45 My invention relates to the means by which the movements of the knee and ankle joints are controlled, and the necessary rigidity is maintained during the cessations in those movements.

50 To enable those skilled in the art to make and use my invention, I will proceed to describe its construction and operation.

A, B, and C, (Figs. 1, and 2,) represent the thigh, leg, and foot, which may be made 55 of any known material, of sufficient strength to support the weight of the body. The leg

is connected with the thigh and with the foot, by hinge joints, a, b, ball and socket joints, or any other connection most suitable to represent the knee and ankle joints; 60 the thigh piece, A, and leg piece, B, being provided with stops, f, f, which come in contact when the knee is straight, and thus prevent its being thrown too far back. The thigh and leg may be made hollow, or the 65 latter must have sufficient space within it, for the passage of a rod, D, which is connected at its lower end with the foot, in front of the ankle joint, b, and which works through a guide or guides, c, c, under one of which, or attached in some suitable way to the leg, B, or spring, d, coils round the rod, to which it is firmly secured. The effect of this spring is to throw down the toe or front 70 end of the foot. The upper end of the rod 75 is furnished with a roller, e, which works in contact with the face of a curved bar, E, which is rigidly attached to the thigh at the back of the knee joint, a. The curved bar proceeds from its place of attachment, 80 for some distance in a straight line, then forms a hollow curve, g, on its face, next a smaller rounded curve, h, then for a very short distance is nearly straight, and the terminating portion forms a small arc, (i), 85 which fits to the periphery of the roller at the top of the rod, D.

In bending the knee, the curved bar, E, works under the roller, e; but when the leg is straightened, as shown in Fig. 1, in black, 90 which figure represents the foot thrown forward and placed on the ground, as when the step is made; the terminating curve, i, of the curved bar, fits to the back and under parts of the roller. The back of the roller coming 95 in contact with the bar, prevents the possibility of bending the knee without raising the roller, e, and rod, D, and holds the stops, f, in contact, making the knee perfectly stiff. The extremity of the bar, E, holds up the 100 roller, e, against the tension of the spring, d, and while it allows the front of the foot to bend upward from the ankle with a moderate pressure, holds the ankle stiff, when no pressure is used, and limits its downward movement. When the upper part of the limb is moved forward, in taking the succeeding step with the opposite foot,—the limb is shown in red color in Fig. 1, making 105 this movement,—the ankle is the first joint in which any movement is made; and the bend which there takes place, moves the rod,

D, and its roller, *e*, upward from the position where they hold the knee stiff. As the heel is raised preparatory to lifting the whole foot, the ankle is still further bent, 5 and the rod further raised, and there is a tendency to bend at the knee; this tendency is allowed to operate; and the roller, *e*, moves up the rounded curve, *h*, of the curved bar, until it reaches a position where it will 10 rest, which will be about the position indicated by dotted circles in the red portion of Fig. 1. By stopping in that position, the roller and rod keep the toe raised, and the knee slightly bent, during the early portion 15 of the next step; but as the foot reaches the end of its forward movement, the lower part of the limb acquired such momentum that, when the forward movement from the thigh ceases, the knee is straightened by its 20 continued motion; and the roller, *e*, descending the curve, *h*, throws down the toe, and arrives at the hollow curve, *i*, where it again locks the knee stiff, with the foot in position to be brought flat, or nearly so, upon the 25 ground.

To bend the knee for sitting down, the weight requires to be thrown upon the front of the foot, and the ankle bent enough to raise the roller, *e*, high enough to run over 30 the rounded curve, *h*, when no further ob-

stacle to the bending is encountered, until it is bent as far as necessary, when the back stops, *j*, *j*, of the leg and thigh, meet; the roller following the hollow curve, *g*, and thereby descending far enough to allow the 35 foot to come down flat. No obstacle is offered to the straightening of the leg again, but that of the spring, *d*, during the early part of the movement, which will be easily overcome by placing the foot flat on the 40 ground, and raising the body.

What I claim as my invention, and desire to secure by Letters Patent, is—

The combination of the rod, *D*, which is attached to the foot, and moves upward 45 and downward, within the leg or lower part of the limb, the spring, *d*, applied to the rod, and the curved bar, plate, or way, *E*, attached to the thigh or upper part of the limb, the whole operating substantially as described, to lock the knee stiff and control the position of the foot, until the ankle is bent on throwing the body forward, and retain the foot in its bent position at the ankle, 50 until the knee is again straightened, as herein fully set forth.

DAVID B. MARKS.
